UNITED STATES PATENT OFFICE.

MAX C. MILLER, OF CUMBERLAND HILL, RHODE ISLAND, ASSIGNOR TO JENCKES KNITTING MACHINE COMPANY, OF PAWTUCKET, RHODE ISLAND, A CORPORATION OF RHODE ISLAND.

CIRCULAR-KNITTING MACHINE.

1,322,716.

Specification of Letters Patent. Patented Nov. 25, 1919.

Application filed August 20, 1917. Serial No. 187,213.

To all whom it may concern:

Be it known that I, MAX C. MILLER, a subject of the Emperor of Germany, residing at Cumberland Hill, in the county of Cumberland and State of Rhode Island, have invented certain new and useful Improvements in Circular-Knitting Machines; and I do hereby declare the following to be a full, clear, and exact description of the invention, such as will enable others skilled in the art to which it appertains to make and use the same.

The invention relates to circular knitting machines such as are adapted for use in knitting seamless stockings or half-hose.

The object of the invention is to provide a novel and improved construction of needle operating and controlling cams whereby the needles may be conveniently leveled below the web-holding sinkers in doing transfer work, thereby enabling the transfer quills to be accurately positioned by the sinkers, and the transfer of the stitches therefrom to the needles to be quickly and accurately effected. To this end the invention comprises the features of construction and combinations of parts hereinafter described and referred to in the claims.

The various features of the invention will be readily understood from an inspection of the accompanying drawings and the following detailed description of the constructions illustrated therein.

In the drawings, Figure 1 is an elevation showing a portion of the interior of the cam cylinder of a machine embodying the invention; Figs. 2, 3, 4 and 5 are similar views showing the parts in different positions; Fig. 6 is a sectional elevation on line 6, Fig. 1; Fig. 7 is a sectional elevation on line 7, Fig. 2; Fig. 8 is a sectional detail on line 8, Fig. 1; and Figs. 9, 10 and 11 are diagrammatic views showing a modified form of the invention.

In the drawings the invention is shown as embodied in a machine in which the needles 2 are mounted in a rotary needle cylinder 4 which may be rotated and reciprocated in the usual manner by any suitable or well-known mechanism. The instep needles which are not active during the reciprocatory knitting on the heel and toe, are provided with long butts, indicated in Fig. 6, while the needles which are active during

reciprocatory knitting are provided with short butts, indicated in Fig. 7, as is usual in this class of machines. The stitch forming cams which form the knitting waves in the needles comprise the stitch cams 6 and 8 and the coöperating needle raising side cams 10 and 12 which raise the needles to the tuck level after they have passed under the corresponding stitch cams. The stitch cam 6 is active during both rotary and reciprocatory knitting, and may be termed the rotary stitch cam, while the stitch cam 8 is active only during reciprocatory knitting upon the heel and toe, and may be conveniently termed the "heel stitch cam." A center cam plate 14 is arranged between the stitch cams and is provided with inclined edges underlying the needle depressing surfaces of the stitch cams and coöperating therewith to form needle passages which determine the path of movement of the needle butts. This cam is also provided with a groove or needle passage 16 which is arranged to register with the needle butts when the needles are at the tuck level, and through which the needle butts pass in doing transfer work, as will be more fully described. The stitch cams are mounted to yield vertically so that each cam may be moved down out of the needle path by the engagement of the needle butts with the back of the cam when it acts to raise the needles from the tuck level to the clear level. In order that the needle butts may depress the cams into inactive position, cover cam plates 18 and 20 are arranged over the stitch cams in such position that a passage for the needle butts is formed when the corresponding stitch cam is in its depressed position, the passage being closed by the upper end of the stitch cam when in its raised or active position. The manner of mounting the stitch cams is indicated in Fig. 8, in which the cam 6 is shown secured on the inner end of a radially arranged arm 22, the outer end of which is pivoted in a support 24. The spring 26 interposed between the arm and the base of the support tends to hold the stitch cam in its raised or active position, which is determined by the stop screw 28. The stitch cam 8 is similarly mounted and supported, and the support 24 for this cam is mounted for radial movement on a guide-plate 30 secured upon a fixed supporting plate 32. The slide is retained

on the guide-plate by a screw 34 which passes through a slot in the slide and is provided with a head overlying its upper surface. The slide may be moved manually in 5 the manner hereinafter described, or may be thus moved automatically through suitable connection with the operating or pattern mechanism. The slide for the cam 6 may be moved radially to facilitate the 10 movement of the needle cylinder or for inspection.

To enable the needles to be leveled with their hooks below the web-holding sinkers 36, the needle raising cams 10 and 12 and the 15 center cam plate 14 are mounted upon a vertically movable ring or segment 38. During the knitting the ring 38 is held in its raised position by a cam ring or segment 40, the upper edge of which is provided with 20 a series of cams 42 engaging rolls 44 on the ring 38, as indicated in Figs. 1 and 6.

During rotary knitting the needle butts pass through the cams in the path indicated in Fig. 1. When the knitting is completed 25 and the needles are to be leveled for the transfer of the stitches of a ribbed top there-to, the stitch cam 8 is withdrawn from the path of the short butts while the long butts are passing, so that they will pass it and go 30 through the needle passage 16. During the passage of the short butts the stitch cam 8 is moved radially out of the path of the long butts, so that they also pass through the needle passage 16, all the needles except 35 those passing under the stitch cam 6 being brought to the truck level. The cam ring 40 is now turned toward the right in Fig. 1, thus lowering the needle elevating and center cams into the position indicated in 40 Fig. 2. The needle cylinder is then turned through a revolution, and during this movement of the needle cylinder a leveling cam 46 acts to level the needles with their hooks substantially at the level to which they are 45 drawn by the stitch cams during the knitting operation, as indicated in Figs. 2 and 7. As shown, the leveling cam 46 is pivotally mounted in a bearing 48 on the ring 38, and is held in position with its upper end bearing 50 against the under side of the cover cam 20 by a coiled spring 50. The lower end of the cam overlies the upper side of the needle raising cam 12, so that a needle passage is formed between the cams. After the needles 55 have been leveled the latch ring of the machine is raised and the machine is stopped in case the operations above referred to have been automatically effected. The quill ring carrying the top which is to be transferred 60 to the needles is then applied to the web-holding sinkers, the quills of the ring entering the spaces between the sinkers so that they accurately register with the needles. The cam ring 40 is then turned toward the 65 left in Fig. 2, raising the cams 10, 12, 14 and

46 into the position indicated in Fig. 3. The effect of this movement of the cams upon the needle butts is also indicated in this figure. The needle cylinder is then turned until all the needles have been raised into the quills, 70 the needle butts during this operation passing through the needle passage 16 so that they are not raised above the tuck level. The quill ring is then removed, the latch ring restored to position, and the needle cylinder rotated through at least one revolution. During this revolution of the needle cylinder the needle butts pass in front of the stitch cam 8 through the groove 16 under the stitch cam 6 and are returned to the 80 tuck level by the cam 10, so that the needles will draw the loops of the transferred top down under the nibs of the sinkers without casting off the loops. The stitch cam 8 is then moved into the path of the long butts 85 while the short butts are passing, and after the short butts have passed its inward movement is completed so that first the long butt and then the short butt needles are raised to the clear level and passed over the center 90 cam 14, as indicated in Fig. 5. The yarn is led to the needles in advance of the first long butt passing up into the clear level so that the knitting is resumed.

Instead of withdrawing the stitch cam 8 95 in the manner above described in leveling the needles, the cam ring 40 may be moved into the position indicated in Fig. 2 to lower the needle raising and centering cam before the stitch cam is withdrawn. In such case 100 the cam 8 will be held in the dotted line position indicated in Fig. 2 by the needle butts overlying it until the needle cylinder is rotated, when these needle butts will engage the stitch cam 6 and be drawn down to the 105 knock over level.

In Figs. 9 to 11 a different arrangement of cams is shown. In this construction the stitch cams 52 and 54 are fixed with relation 110 to the needle elevating cams 56 and 58, and cover cams 60 and 62 are arranged over the stitch cams to deflect the needle butts passing over the back of each cam down into a level to engage the forward ends of the opposite cam. The center cam in this construction is formed in two sections 64 and 66 which are separated to form a needle passage 68 which is at the tuck level, and through which the needle butts pass when the needles are raised into the quills of the transferred quill cup. The section 66 is secured in fixed relation to the stitch cams while the section 64 is secured to the vertically movable ring 70 which carries the needle raising cams 56 and 58. The needle 115 raising cam 58 is provided with an upper section or supplemental cam 72 which is mounted in fixed vertical relation to the switch cam 54, but may be moved radially in and out. The vertically movable cam- 120

carrying ring 70 is raised and lowered by a cam ring 74 provided with a cam 76 engaging rolls 78 on the ring 70.

The mode of operation in leveling and transferring is similar to the mode of operation already described with reference to Figs. 1 to 5. When the needles are to be leveled the cam 72 is withdrawn from the path of the short butts during the passage 10 of the long butts, and is withdrawn from the path of the long butts during the passage of the short butts, so that the needles pass under the heel stitch cam 54 and through the needle passage 68, as indicated in Fig. 10. The cam ring 70 is then lowered to bring the cam into the position indicated in Fig. 3, and the needle cylinder rotated to level the needles with their hooks substantially at the level to which they are 20 drawn by the stitch cams during the knitting, as indicated in Fig. 11. The quill cup is then applied and the cams raised into normal active position. The needle cylinder is turned to project all the needles into 25 the quills, the needles being raised to the tuck level only since they pass through the needle passages, as indicated in Fig. 10. After the quill ring is removed, the needle cylinder is given at least one turn to bring 30 the loops of the transferred top below the nibs of the sinkers, and then knitting is resumed by returning the cam 72 into active position, the cam being first brought into the path of the long needle butts while the 35 short needle butts are passing, and thereafter being brought into the path of the short needle butts while the long needle butts are passing.

While it is preferred to employ one of 40 the forms of the invention shown and described, it will be understood that these forms are not essential to the broader features of the invention, and may be varied and modified as found desirable or best 45 suited to the specific construction, arrangement and mode of operation of the knitting and needle-operating cams of the machine in which the invention is to be embodied.

Having explained the nature and object 50 of the invention and specifically described construction in which it may be embodied, what is claimed is:

1. A circular knitting machine, having in combination, stitch cams and side cams 55 for raising the needles to the tuck level movable vertically from a position to operate with the stitch cams to a position below the level to which the needles are drawn by the stitch cams.

60 2. A circular knitting machine, having, in combination, stitch cams, needle raising

cams, a center cam between the stitch cams having a needle passage at the tuck level, means for directing the needles over the center cam or through its needle passage, 65 and means for moving the needle raising and center cams from active position to a position below the level to which the needles are drawn by the stitch cams.

3. A circular knitting machine, having, 70 in combination, stitch cams, cooperating side cams for raising the needles to the tuck level, and means for lowering the side cams and leveling the needles below the stitch cams. 75

4. A circular knitting machine, having, in combination, stitch cams, coöperating needle raising cams, means for lowering the needle raising cams and leveling the needles below the stitch cams, means for 80 raising the needles to the tuck level and for thereafter restoring them to knitting relation with the stitch and needle raising cams.

5. A circular knitting machine, having, 85 in combination, stitch cams, side cams for raising the needles to the tuck level, a vertically movable carrier for the needle raising cams, and a cam ring for raising and lowering the carrier. 90

6. A circular knitting machine, having, in combination, stitch cams, needle raising cams, a center cam between the stitch cams, a vertically movable carrier for the needle raising and center cams, and a cam ring 95 for raising and lowering the carrier.

7. A circular knitting machine, having, in combination, stitch cams, needle raising cams, means for leveling the needles at substantially the level to which they are drawn 100 by the stitch cams, means for raising all the needles to the tuck level and for thereafter restoring them to knitting relation with the stitch and needle raising cams.

8. A circular knitting machine, having, 105 in combination, rotary and heel stitch cams, and side cams coöperating therewith in forming the knitting waves mounted for vertical movement from knitting position to a position below the level to which the needles 110 are drawn by the stitch cams.

9. A circular knitting machine, having, in combination, cams for forming the knitting waves in the needles during rotary and reciprocatory knitting, comprising stitch cams, one of which is radially movable out of and into position to act on the needles, and side cams mounted for vertical movement from knitting position to a position 115 below the level to which the needles are 120 drawn by the stitch cams.

MAX C. MILLER.
